Application filed January 11, 1933. Serial No. 46,783. Term of patent 3½ years.

To all whom it may concern:

Be it known that I, THOMAS R. ATKINS, a citizen of the United States, residing at Cliftondale, in the county of Essex and State of Massachusetts, have invented a new, original, and ornamental Design for a Shoe, of which the following is a specification, reference being had to the accompanying drawing, forming part thereof, in which—

Fig. 1 is a view in side elevation and Fig. 2 is a top plan view of a shoe showing my new design.

The essential feature of my design is in the ornamental effect produced by the series of groups of three perforations of pointed, curved formation arranged in various portions of the shoe.

I claim:

The ornamental design for a shoe as shown and described.

In testimony whereof, I have signed my name to this specification.

THOMAS R. ATKINS.
